United States Patent Office

Des. 182,935
Patented May 27, 1958

182,935

ELECTRIC SHAVER

Raymond A. Smith, Bradfordwoods, and Roger I. Protas, Pittsburgh, Pa., assignors to Schick Incorporated, Lancaster, Pa., a corporation of Delaware

Application October 17, 1957, Serial No. 48,193

Term of patent 14 years

(Cl. D22—3)

Fig. 1 is a front elevation of an electric shaver, showing our new design;

Fig. 2 is a right hand side elevation;

Fig. 3 is a rear elevation;

Fig. 4 is a left hand side elevation of the electric shaver shown in Fig. 1;

Fig. 5 is a top plan view; and

Fig. 6 is a bottom plan view thereof.

We claim:

The ornamental design for an electric shaver, substantially as shown.
